(57) **CLAIM**

I claim the ornamental design for a motion sensor, as shown and described.

DESCRIPTION

FIG. 1 is a front perspective view of a motion sensor of the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along the line 8-8 in FIG. 2 with the internal parts being omitted; and,

FIG. 9 is a referential front perspective view thereof showing detection sensors with hoods.

The broken line showing of motion sensor is included for the purpose of illustrating environment and forms no part of the claimed design.
